GAME SHEARS

Alwin J. Stahel, New Brighton, Minn., assignor to
Arthur Salm Inc., Chicago, Ill.

Filed June 10, 1970, Ser. No. 23,431

Term of patent 14 years

Int. Cl. D8—02

U.S. Cl. D8—52

FIG. 1 is a front elevational view of game shears showing my new design;
FIG. 2 is a top plan view;
FIG. 3 is a bottom plan view;
FIG. 4 is a rear elevational view;
FIG. 5 is a left end elevational view; and
FIG. 6 is a right end elevational view.

I claim:

The ornamental design for game shears, substantially as shown.
